Primary Examiner — Stacia A Cadmus(74) *Attorney, Agent, or Firm* — RatnerPrestia(57) **CLAIM**

The ornamental design for a wheel for a motor vehicle, as shown and described.

DESCRIPTION

FIG. 1 is a front elevation view of a wheel for a motor vehicle;

FIG. 2 is a side elevation view thereof;

FIG. 3 is a top plan view thereof; and,

FIG. 4 is a front perspective view thereof.

The broken lines in the drawings are for illustrative purposes only, and form no part of the claimed design.
